HOWARD K. KING, OF PHILADELPHIA, PENNSYLVANIA, ASSIGNOR TO CHAMBERS BROTHERS COMPANY, A CORPORATION OF PENNSYLVANIA.

SHEET FOLDING.

Application filed July 1, 1927. Serial No. 202,874.

The invention relates to sheet folding. The object is to provide improved method and means for folding sheets, especially two or more sheets together so that they will be closely associated at the crease.

Where two sheets or two layers of a sheet are simultaneously creased together by the usual method or means, it sometimes happens, due to the peculiar characteristic or quality 10 of the sheet, that the said sheets or layers are not maintained with their creases in sufficiently close relationship. That is to say, the crease of one sheet or layer may slip slightly away from the crease of the other sheet or 15 layer. This may be in part due to the previous treatment of the sheet, and to the friction of the striking blade as it is withdrawn from the sheet, after the sheet has come under the control of the rollers. It is known that 20 the striking blade must carry the sheet at its fold or crease sufficiently down between the rollers so that the rollers will operate positively upon the sheet, but it also is necessary that the striking blade must not go down 25 sufficiently between the rollers to be pinched or engaged thereby. These conditions require a nice adjustment of the movement of the striking blade, and with some sheets it is practically impossible to carry the sheets 30 sufficiently into the control of the rollers to prevent slipping, especially of one sheet from another where two or more sheets or layers are struck together between the rollers.

The purpose of the present invention is to 35 provide method and means whereby the crease is carried well within the control of the rollers without any danger of the blade being caught by the rollers, and without requiring any especially fine adjustment of the 40 movement of the striking blade. By bringing the layers at the crease into positive engagement of the rollers all tendency for one layer to slip from another at the crease is obviated.

45 This end is accomplished by engaging the sheets on the line of crease at separated points or places, and engaging the sheets between the rollers at different points or places, so that the means for bringing the sheets under

control of the rollers operate at points alternating with the points of roller engagement. In this way the sheets are carried well down into roller engagement without danger of the striking blade becoming engaged with 50 said rollers.

55 Referring to the drawings, which illustrate merely by way of example suitable means for effecting my invention:—

Fig. 1 is a view showing the roller and striking blade in cross-section, the blade-arm 60 being in elevation.

Fig. 2 is a plan view of the rollers.

Fig. 3 is an elevation of the striking blade.

Fig. 4 is a section on line 4, 4 of Fig. 2, on 65 an enlarged scale.

Fig. 5 is a section on line 5, 5 of Fig. 2 on an enlarged scale.

Fig. 6 is a view similar to Fig. 1, on a reduced scale, showing a modification of the arrangement of the sheets.

70 Fig. 7 is a fragmentary sectional view on an enlarged scale.

Similar numerals refer to similar parts throughout the several views.

In Figs. 1 and 2 are shown the parallel 75 folding rollers 10 and 11 having the grooves 12, into which project the strippers 13. These rollers are of the usual type, except that the extensions between the grooves 12 are of different diameters. That is they are provided 80 with extensions 14 which are of maximum diameter. The opposite pairs of extensions 14 of the two rollers have their peripheries in close proximity in order to engage the sheets and carry them between and through the rollers.

85 Other extensions 15 are of substantially reduced diameter, so that opposite pairs of extensions 15 are sufficiently separated as to their peripheries to provide ample space for the projecting extensions 16 of the striking 90 blade 17, to pass with the sheets between said rollers approximately to a plane common to their axes. Other extensions 18 are slightly greater in diameter than the diameter of the extensions 15 and slightly less in diameter 95 than the diameter of the extensions 14. These tend to maintain the fold or crease of the sheet in proper alignment with the line of en-

gagement of the roller extensions 14 on the one side and with the line of engagement of the blade extensions 16 on the other side.

In Fig. 1 the sheets 19 and 20 are shown 5 as traveling in separated formation over the slot forming plates 21 and 22 respectively. In Fig. 6, the sheets or layers 23 and 24 are shown traveling together, that is, one resting upon the other, over the lower plate 22.

10 The striking blade 17 carried on the oscillating arm 25, is provided with a number of extensions 16, which project beyond the normal engaging edge 26 of the blade 17. In other words these projecting extensions 16 15 are disposed at separated intervals, corresponding in position with that of the roller extensions 15.

Fig. 7 is a fragmentary section showing 20 the extensions 16 of blade 17 projecting down to the common plane of the axes of the two rollers but well separated from the opposite peripheries of the roller sections 15.

In operation.

25 When the striking blade 17 is lowered, the projecting extensions 16 engage the sheets or layers 19 and 20 or 23 and 24 and carry them down between the rollers 10 and 11 so that the pairs of extensions 14 will engage the sheets and crease the same along a straight 30 line of fold and carry them between and through the rollers in the usual way, so that the folded sheet will travel beneath the guide rods 27 in the direction of the arrow in Fig. 35 1. Because of the reduced diameters of the extensions 15, ample space is permitted for the projecting extensions 16 to pass well between these pairs of extensions to approximately the common plane of the axes of the 40 two rollers. This assures the folded edge of the sheets being brought well within the grip of the several pairs of roller extensions 14 so that there will be no slip of one sheet with respect to the other; and also, because of the 45 ample space between the several pairs of extensions 15, into which the blade extensions 16 project, there is no possibility of the blade being gripped by the rollers and there is no undue friction between the blade and the

sheet to cause displacement between the sheets 50 thus folded together.

What I claim is:-

1. The method of folding sheets which consists in exerting actuating force on the sheet 55 at intervals on a straight line of crease and simultaneously to cause the same to be subjected to creasing pressures at other intervals on said line of crease alternating with the first intervals.

2. The method of folding sheets which consists in exerting actuating force on a plurality of superimposed sheets, moving in parallel paths of travel at intervals on a straight line of crease to cause the same to be subjected to creasing pressures at other intervals 65 on said line of crease alternating with the first intervals.

3. In a sheet folding machine, the combination of a continuous striking blade having sheet-engaging edge extensions spaced at intervals along its length, and slightly projecting beyond the intervening edge extensions 70 and a pair of folding rollers, each having extensions of relatively reduced diameter arranged at corresponding intervals, to form 75 spaces for the said projecting edge extensions.

4. In a sheet folding machine, the combination of a striking blade having sheet-engaging projecting extensions spaced at intervals along its length, and a pair of folding rollers 80 having extensions of relatively reduced diameter arranged at corresponding intervals, to form spaces for the sheet-engaging blade extensions, said rollers having other extensions of relatively greater diameter cooperat- 85 ing to grip the sheet.

5. In a sheet feeding machine, the combination of a striking blade having sheet-engaging projecting extensions spaced at intervals, and a pair of folding rollers cooper- 90 ating therewith, said rollers each having extensions of different diameters so arranged that the diameters of the several extensions of one roller will correspond respectively with the diameters of the opposite extensions 95 of the other roller, as and for the purpose described.

HOWARD K. KING.
